UNITED STATES PATENT OFFICE

130,599

DESIGN FOR A BIRD ORNAMENT FOR CLOTHESLINE OR SIMILAR ARTICLE

Daisy Myrtle Loyd, Portland, Oreg.

Application February 24, 1941, Serial No. 99,199

Term of patent 7 years

To all whom it may concern:

Be it known that I, Daisy Myrtle Loyd, a citizen of the United States, residing at Portland, in the county of Multnomah and State of Oregon, have invented a new, original, and ornamental Design for a Bird Ornament for Clothesline or Similar Article, of which the following is a specification, reference being had to the accompanying drawing, forming part thereof.

Fig. 1 is a front elevational view of a bird ornament for a clothesline or similar article, showing my new design; the opposite side being plain; and

Fig. 2 is an edge elevational view thereof.

I claim:

The ornamental design for a bird ornament for a clothesline or similar article, substantially as shown and described.

DAISY MYRTLE LOYD.
